GEORGE FERGUSON, OF WOLLASTON, MASSACHUSETTS, ASSIGNOR TO UNITED SHOE MACHINERY CORPORATION, OF PATERSON, NEW JERSEY, A CORPORATION OF NEW JERSEY.

RUBBER-SOLE SHOE.

1,348,163.

Specification of Letters Patent.

Patented Aug. 3, 1920.

Application filed December 11, 1917. Serial No. 206,688.

To all whom it may concern:

Be it known that I, GEORGE FERGUSON, a citizen of the United States, residing at Wollaston, in the county of Norfolk and 5 State of Massachusetts, have invented certain Improvements in Rubber-Sole Shoes, of which the following description, in connection with the accompanying drawings, is a specification, like reference characters on 10 the drawings indicating like parts in the several figures.

The present invention relates to improvements in shoes and to improvements in shoe soles, particularly vulcanized rubber soles. 15 The term rubber as herein used is not intended to be limited to a material the major part of which is rubber, but is used herein generically to include various rubber containing materials such as the so-called fiber 20 soles now used extensively, as well as other similar materials.

Objects of the invention are to eliminate various disadvantages incident to the employment of rubber soles as heretofore 25 made, and generally to improve the construction of rubber sole shoes to the end that rubber sole shoes of superior appearance and fitting qualities may be produced.

With these objects in view and in accordance with an important feature of the 30 invention, the illustrated shoe has a vulcanized rubber sole characterized by a heel seat portion the outer surface of which is molded to provide a continuously convexed heel 35 seat substantially complementary to the concaved heel seat of a previously completed heel and arranged to terminate a distance within the periphery of the heel seat portion of the shoe, whereby the heel seat portion 40 of the shoe is concealed by the heel when it is attached to the shoe, the margin of the heel may be seated upon the firm foundation afforded by the overlasted shoe upper and counter materials and a substantially rigid attachment of the heel to the 45 shoe may be effected. Also with the use of a rubber sole having a heel seat molded in this manner it is unnecessary to perform the usual hand heel fitting operation as with 50 the rubber soles now available and a more accurately shaped and uniform heel seat is obtainable.

In accordance with another feature of the invention, the upper surface of the sole

herein illustrated is molded so as to produce 55 a marginally extending shoe upper attaching element the thickness of which at its base is substantially less than the thickness of the upper attaching element above its base. In the illustrated preferred embodiment of the invention the upper attaching element consists of an upstanding sewing rib having a substantially vertical outer wall and an undercut or downwardly and outwardly inclined inner wall. When attaching 60 a shoe upper to the sole by means of a sewing rib of the illustrated construction, the channel guide of the sewing machine which engages the inner wall of the rib is maintained in a position at the extreme base 65 of the rib, thus tending to hold the shoe in the proper field of operation of the sewing instrumentalities so that the inseam connecting the shoe upper to the sewing rib is properly located at the base of the sewing 70 rib. Consequently a tighter and stronger inseam is obtained and the operator is assisted in manipulating the shoe during the 75 sewing operation.

A further feature of the invention consists in a vulcanized rubber sole having a series of radially disposed alternate ribs and 80 grooves formed on the upper surface of the sole with the outer ends of the ribs and 85 grooves terminating a distance inwardly from the periphery of the sole. By thus leaving a narrow surface on the sole outside of the ribs and grooves it is possible to trim and buff the edge of the sole without producing a ragged and broken sole edge face 90 and a neater and better appearing sole edge is obtainable.

Still another feature of the invention resides in providing a molded and vulcanized rubber sole for turn shoes with a stitch receiving element along its upper marginal surface and with means vulcanized in its shank portion additional to the rubber of the sole adapted to retain a longitudinally curved shank stiffening member in position for it to maintain the shank portion of the sole in longitudinal conformation therewith. This shank stiffener retaining means is preferably incorporated in the shank portion of the sole so as to leave no indication of its attachment on the tread surface of the sole. In the preferred practice of the invention the sole is produced by molding along the 100

95

100

105

- upper marginal surface of the sole a sewing rib to which to attach the shoe upper and molding into the shank portion of the sole a shank stiffener receiving means which will 5 not obstruct the turning of the shoe right side out during its manufacture. The sole thus produced is employed in making the shoe by a procedure which consists in assembling the sole and the shoe upper inside 10 out upon a last and sewing the upper to the sewing rib on the sole, turning the shoe right side out before incorporating the shank stiffener in the shoe, applying the shank stiffener to the previously prepared 15 stiffener receiving means and thereafter lasting and completing the shoe-making operations on the shoe. As herein illustrated, this shank stiffener engaging member comprises a wire stud the base of which is anchored in the sole between its upper and 20 lower surfaces, the head projecting above the upper surface of the sole and adapted to be attached to a shank stiffener incorporated in the shoe. This attachment serves 25 to hold the shank of the sole against the under side of the shank stiffener and prevent it from returning to its normally flat condition as it otherwise would because of its character.
- 30 Other objects and features of the invention will be apparent from the following description and claims when considered in connection with the accompanying drawings and the invention will be pointed out in the 35 appended claims.

In the drawings,—

Figure 1 is a perspective view of a sole constructed in accordance with the present invention;

40 Fig. 2 is a perspective view, partly in section, showing a shoe made with the sole illustrated in Fig. 1 and illustrating the application of the heel to the shoe;

45 Fig. 3 is a perspective view partly in section illustrating the use of the shank stiffener engaging member, and

50 Fig. 4 is a sectional view of the sole through the forepart and illustrating the construction of the sewing rib of the sole and the stitch impressed formation of the extending edge of the sole.

For purposes of illustration the invention is herein shown as embodied in a vulcanized rubber sole which is applicable to the manufacture of a turn shoe although it is apparent that the invention may be employed to advantage in soles for shoes of other types.

55 Referring to the drawings, the sole 2 consists of a vulcanized rubber compound body 60 hereinafter generically referred to as rubber, molded to the general shape of a sole through the forepart and shank. This rubber body is provided with a sewing rib 4 on its upper surface to enable a shoe upper 65 to be attached to the sole by single faced

stitches 5 such as required by the turn method of making shoes. The rubber body itself ordinarily does not provide sufficient strength to receive and hold such stitches. Therefore, the upper surface of the body 2, 70 as herein illustrated is reinforced with a layer of fabric material 6. Conveniently the sole may be provided with the sewing rib 4 by molding the sole at the time the sole is vulcanized in suitably shaped dies which 75 are formed and arranged to raise a portion of the rubber and fabric 6 above laterally adjacent surfaces of the sole, the raised portion extending marginally at the sole and constituting the sewing rib. It is not only 80 exceedingly important but also difficult to locate the inseam stitches at the base of a sewing rib in which the inner and outer walls are substantially vertical as heretofore provided. If the stitches 5 are not so located a weak seam is secured and the upper 85 is not drawn into the angle between the outer wall of the rib and the feather of the sole with the proper amount of tension. This is due to a certain extent to the fact 90 that the sewing needle tends to find the path of least resistance in penetrating the rib, which is, of course, toward its top. Also, the operator is apt to lower the shoe below its proper position relatively to the sewing needle and other operating instrumentalities. With this in mind the sewing rib 95 4 of the sole has an outer substantially vertical wall 8 against which the upper may properly be tensioned, and an inner wall 10 100 which is inclined upwardly and inwardly so as to present an undercut surface. Preferably this is done by thickening the top portion of the sewing rib so as to produce a broad flat top rather than decreasing the 105 thickness of the sewing rib at the base so that the strength of the between-substance which constitutes the base of the sewing rib is not impaired or weakened by the inclined inner wall of the rib. In the operation of 110 securing the shoe upper to the sole, the channel guide 12 of the sewing machine travels in the angle formed by the inclined wall 10 and the adjacent upper surface of the sole, as illustrated in Fig. 4, and by reason of the inclined wall the channel guide tends to maintain the shoe firmly against the guide without any special care on the part of the operator. Consequently the shoe 115 is maintained in such position that the several sewing instrumentalities, as the awl and the needle indicated in Fig. 4 of the drawings, are enabled to form the stitches or inseam along a line located at the extreme base of the sewing rib 4. Thus the shoe upper may be drawn under greater tension and with more accuracy into the angle between the outer vertical wall of the rib 4 and the feather of the sole than where the inseam is formed "high" on the sewing rib, as results 120 125 130

- when the operator fails to hold the shoe so that the channel guide 12 travels along the extreme base of the rib. The inclined inner wall 10 of the sewing rib is equivalent to the 5 channel provided in a leather turn sole so that the rubber sole of the present construction may be used during the sewing operation with the same facility as a leather shoe.
- 10 In order to provide a neat finish and appearance for the edge of the sole which projects beyond the sides of the shoe upper, the upper feather surface of the sole 2 is provided with a series of radially disposed alternate 15 ribs and grooves 16. These ribs and grooves, which may conveniently be formed in the sole 2 during its molding and vulcanization, correspond somewhat to the stitched impression formed on the feather 20 surface of a leather sole shoe and serve to accentuate the crease between the extension of the sole and the upper so as to give the appearance of a sewed shoe as distinguished from the more or less heavy appearance 25 characteristic of a vulcanized rubber compound shoe. As shown in Fig. 4, the alternate ribs and grooves 16 terminate a short distance inwardly from the periphery 18 of the sole at their outer ends and extend to 30 the sewing rib at their inner ends. By terminating the ribs and grooves or corrugations 16 within the periphery of the sole a sufficient margin of the sole remains to enable its edge face to be cleaned and buffed 35 during the finishing operations on the shoe without producing a ragged and broken edge face on the sole. It has been found practically impossible properly to buff the edge face of the sole 2 so as to maintain the 40 desired well defined termination of the sewing ribs and grooves. Moreover, in molding and vulcanizing a sole in which the ribs and grooves 16 extend clear to the edge of the sole a "fin" of rubber material is formed 45 along the upper edge of the sole, which fin cannot readily be removed without trimming away a considerable part of the edge face of the sole which involves an unnecessary amount of labor and expense.
- 50 The heel end 20 of the sole, as shown in Figs. 1, 2 and 3, instead of being of sufficient size entirely to cover the heel seat of the shoe being made is so formed as to terminate a uniform distance within the 55 periphery of the heel seat while presenting a sufficient surface to offer a firm foundation upon which to seat the heel. Also, the heel seat end of the sole is molded so as to present a surface 22 which is uniformly con- 60 vexed transversely and rearwardly to its edge to fit within the concaved heel seat of a previously completed heel 24. In the attachment of a previously completed heel to the shoe, as, for example, a wooden heel, it 65 is desirable that the margin 25 of the heel
- seat surface of the heel be seated directly upon the margin 26 of the heel seat of the shoe formed by the overlasted portion of the counter and shoe upper materials without an intervening layer of rubber material 70 which comprises the sole. One reason for this is that wooden heels are usually of considerable height and, therefore, need as substantial and firm foundation and attachment to the shoe as possible, which, of course 75 is not possible with a heel seat formed of rubber material. Also wood heels are invariably covered with the same material that constitutes the shoe upper or they have a contrasting finish and the neat and stylish 80 appearance of the completed shoe demands a continuity of the finish of both the heel and the shoe upper. The heel seat portion 20 of the sole illustrated projects rearwardly from the shank portion of the sole 2 and is 85 of a width to produce a shoulder 28 at either side of the sole at substantially the heel breast line. The outer surface of the heel seat is continuously and uniformly concaved so as to correspond to the convex heel seat 90 surface of the wood heel, as illustrated in Fig. 2, such heels invariably having concaved heel seat surface to enable them properly to be attached to the shoe. These shoulders extend inwardly at substantially 95 right angles to the edge of the sole to the projecting heel seat portion and serve to produce a neat joint between the termination of the sole at the heel breast line and the heel. Also, in use the shoulders 100 constitute abutments to determine the relative location of the heel on the shoe during the heel attaching operation. Heretofore in attaching a wood heel to a shoe having a rubber sole, a hand heel fitting operation was 105 necessary and this hand operation was not entirely satisfactory because the accuracy of the work varied considerably and there was no uniformity in the treatment of the sole to receive the heel in the different shoe factories, some procedures being entirely to eliminate the heel end of the sole, while others cut away various portions of the sole to allow the heel to be placed on the 110 shoe.
- 115 It will be seen that by providing a heel seat portion for the sole which is of an area to terminate within the outer edge of the heel seat, as illustrated in Fig. 1, the margin of the heel is enabled to seat itself directly on the margin 26 of the heel seat of the shoe and completely inclose the projecting heel portion of the sole, but at the same time the sole corresponds to the concaved contour of the major portion of the heel 120 seat of the heel and thus offers a firm seat for the heel throughout. By reason of the heel seat 20 being shaped to cover the major portion of the heel seat of a previously completed heel and of the heel seat of the shoe 125 130

a strong and firm attachment of the heel to the sole may be secured inasmuch as the heel seat portion 20 serves to provide sufficient material to receive the heel attaching 5 nails as indicated in Fig. 3 of the drawings. As such a heel seat is initially molded on the sole it insures absolute accuracy and uniformity.

The shank portion of the sole has a shank 10 stiffener engaging member 32 projecting above the upper surface of the sole, as illustrated in Fig. 1, this member being adapted to engage a longitudinally curved shank stiffener member 34 in the shoe so as to hold 15 the sole against the under side of the stiffener and maintain it in the longitudinal conformation thereof. In the illustrated embodiment of the invention this stiffener engaging member 32 consists of a loop of 20 wire the base portion 38 of which is embedded in the sole so as not to appear on the tread surface of the sole, while the head portion of the member projects above the upper surface of the sole. This projecting portion 25 32, in use, is passed through a hole 39 provided in the longitudinally curved metal shank stiffener 34 and bent rearwardly so as to lie upon the upper surface of the stiffener as shown in Fig. 3. A filling member 40 is 30 subsequently placed upon the inside of the shoe so as to cover the stiffener engaging member 32 and provide a smooth interior for the shoe. Owing to the character of rubber of which the sole 2 is composed and 35 also to the fact that the sole is substantially flat before being applied to the shoe, the sole while conforming to the longitudinal curvature of the shank portion of the last during the time it is on the last tends to return to 40 its normal flat condition immediately upon the shoe being removed from the last. This results in destroying the desired conformation and appearance of the shoe and so distorting and misshaping the shoe that it does 45 not fit the foot of the intended wearer. By providing means attached to the sole and fastened to the shank stiffener, the shank of the sole is maintained in its intended longitudinal conformation after the shoe is re- 50 moved from the last. As shown, a single shank engaging member 32 is provided which is located substantially centrally of the shank portion of the heel, although several of these members may be employed to engage a shank stiffener at a plurality of 55 points in its length.

With a sole such as hereinabove described it is possible to produce a vulcanized rubber sole shoe having a neater appearance and 60 better fitting qualities than was possible, with the rubber soles heretofore available and eliminate certain disadvantages heretofore countenanced in the employment of vulcanized rubber soles in the manufacture of 65 the shoe.

Having fully described my invention, what I claim as new and desire to secure by Letters Patent of the United States is:—

1. As an article of manufacture, an outer sole for shoes comprising a vulcanized rubber body molded to sole contour through the forepart and the shank and having a heel seat portion the outer surface of which is molded to provide a continuously convexed seat substantially complementary to the continuously concaved heel seat of a previously completed heel and which is arranged to terminate a distance within the periphery of the heel seat portion of a shoe and to be concealed by the previously completed heel when it is attached to the shoe. 70

2. As an article of manufacture, an outer sole for shoes comprising a sole shaped vulcanized rubber body characterized by a heel seat portion shaped to terminate a uniform distance within the periphery of the heel seat of a lasted shoe and having its outer surface uniformly convexed transversely and rearwardly to the edge of the heel seat portion. 75

3. As an article of manufacture, a sole for shoes comprising a vulcanized rubber body molded to sole contour through the forepart and the shank and a heel seat portion of less width than the shank of the adjacent sole to form a shoulder on either side of the sole at the termination of the shank for engagement with the breast of a previously completed heel and having its outer surface convexed uniformly and continuously to the periphery so as to engage the uniformly concaved heel seat of a previously completed heel. 90

4. As an article of manufacture a vulcanized rubber sole provided with a marginally extending stitch receiving rib on its upper side for the attachment of a shoe upper and having a heel seat portion shaped and arranged to terminate a uniform distance within the periphery of the heel seat of a lasted shoe and to engage the greater part of the heel seat surface of a previously completed heel when attached to the shoe. 105

5. As an article of manufacture, a sole for shoes comprising a vulcanized rubber body molded to sole contour through the forepart and the shank and having an integral heel seat portion formed and arranged to fit within the concaved heel seat of a previously formed heel and extend over the major portion of the heel seat of the shoe to receive fastening means for permanently attaching the said heel to the sole and to provide a shoulder on either side of the sole at substantially the breast line to engage the breast of the said heel. 115

6. As an article of manufacture, a sole for turn shoes consisting of a vulcanized rubber body portion having its upper surface molded to produce a marginally extending 120

sewing rib presenting a substantially vertical outer wall adjacent to the feather of the sole and an undercut inner wall.

7. As an article of manufacture, a sole for 5 turn shoes consisting of a vulcanized rubber body portion having its upper surface molded to produce a marginally extending sewing element the thickness of which at its base is less than the thickness of the sewing 10 element above the base thereof.

8. As an article of manufacture, a sole for 15 turn shoes consisting of a vulcanized rubber body portion having its upper surface molded to produce a rib projecting above laterally adjacent surfaces of the sole, said 20 rib being shaped to provide a ledge overhanging the base of the rib along its inner edge.

9. As an article of manufacture, a sole for 25 turn shoes consisting of a vulcanized rubber body and a layer of fabric material secured by vulcanization to the upper side of the rubber body with a portion projecting above laterally adjacent surfaces of the sole to 30 produce a reinforced sewing rib the inner wall of which is inclined downwardly and outwardly toward the outer wall of the sewing rib.

10. As an article of manufacture, a sole for 35 turn shoes consisting of a vulcanized rubber body portion having its upper surface molded to produce a marginally extending sewing rib characterized by a decreasing transverse thickness of the sewing rib from the top of the sewing rib to its base.

11. As an article of manufacture, a vulcanized rubber sole provided with a series of radially disposed alternate ribs and 40 grooves extending along the upper marginal surface of the sole, the said alternate ribs and grooves terminating at their outer ends inwardly of the periphery of the sole.

12. As an article of manufacture, a vulcanized rubber sole provided with a marginally extending stitch receiving rib on its 45 upper side and having a plurality of transversely disposed indentations formed on the surface of the sole outside of the stitch receiving rib, the said indentations being terminated within the periphery of the sole so as to leave an unbroken edge face on the sole.

13. As an article of manufacture, a vulcanized rubber outsole provided with a 55 shank stiffener engaging member attached to the outsole in the shank substantially midway between its edges and so as to leave no indication of the attachment on the tread surface of the outsole and having a portion 60 projecting above the upper surface of the outsole adapted to be attached to a shank stiffener member.

14. As an article of manufacture, a vulcanized rubber outsole provided with a 65 shank stiffener engaging member anchored

in the shank portion of the sole between its upper and lower surfaces so as not to appear on the lower surface and having a portion projecting above the upper surface of the outsole in the shank adapted to be attached 70 to a longitudinally curved shank stiffener member.

15. As an article of manufacture, a turn shoe comprising a vulcanized rubber outsole provided with a stitch receiving rib on its 75 upper side, a shoe upper permanently attached to the stitch receiving rib of the outsole, a longitudinally curved shank stiffener member associated with the shank of the outsole, and means additional to the rubber 80 embedded between the upper and lower surfaces of the outsole in the shank and adapted to engage the said stiffener member and maintain the shank of the outsole in longitudinal conformation with the stiffening 85 member.

16. As an article of manufacture, a vulcanized rubber outsole having a shank stiffener engaging member vulcanized in the sole with a portion portion projecting above the 90 upper surface of the sole centrally of the shank and adapted to be attached to a longitudinally curved shank stiffening member midway between its ends for maintaining the shank of the sole in longitudinal conformation with the stiffening member. 95

17. As an article of manufacture, a molded and vulcanized rubber sole for turn shoes provided with a stitch receiving element along its upper marginal surface and having 100 vulcanized in its shank portion means additional to the rubber adapted to retain a longitudinally curved shank stiffening member in place for it to maintain the shank portion of the sole in longitudinal conformation 105 therewith.

18. As an article of manufacture, a molded and vulcanized rubber sole provided with a stitch receiving element along its upper marginal surface and having shank stiffener retaining means additional to the rubber incorporated in the shank portion of the sole so as not to appear on the outer tread surface of the sole and so located as to maintain the shank portion of the sole in conformation with a longitudinally curved shank stiffening member throughout its 110 length. 115

19. As an article of manufacture, a molded and vulcanized rubber sole for turn shoes 120 provided with a stitch receiving element along its upper marginal surface and having vulcanized in its shank portion a shank stiffener holding means which is adapted to permit freedom in turning the shoe and to 125 receive and retain a shank stiffener after the shoe has been turned right side out.

20. That improvement in methods of making turn shoes with molded and vulcanized rubber soles in which the shank portion is 130

- stiffened which consists in molding along the marginal upper surface of a flexible rubber sole a sewing rib to which to attach the upper, molding in the shank portion of the sole a shank stiffener receiving member which will not obstruct the turning of the shoe right side out, assembling the sole and a shoe upper inside out upon a last and sewing the upper to the sewing rib, turning the shoe right side out before incorporating a shank stiffener in the shoe, applying the shank stiffener to the previously prepared stiffener receiving means and thereafter re-lasting the shoe and performing subsequent shoemaking operations to complete the shoe.
21. That improvement in methods of making turn shoes with molded and vulcanized rubber soles in which the shank portion is stiffened which consists in preparing a flexible rubber sole to provide a stitch receiving element along its upper marginal surface and a shank stiffener holding means which will not obstruct the shoe turning operation, assembling the flexible sole and a shoe upper inside out upon a last and sewing the upper to the stitch receiving element, withdrawing the last and turning the shoe right side out, assembling a shank stiffener with the shank stiffener holding means, and thereafter re-lasting the shoe and performing subsequent shoemaking operations to complete the shoe.
22. As an article of manufacture, a sole for turn shoes comprising a vulcanized rubber body portion having its upper surface molded to produce a sewing rib projecting

above laterally adjacent surfaces of the sole, said rib having a broad flat top, and an undercut inner wall.

23. As an article of manufacture, a sole for turn shoes comprising a vulcanized rubber body portion having its upper surface molded to produce a sewing rib projecting above laterally adjacent surfaces of the sole, said rib having a substantially vertical outer wall, a broad flat top, and an undercut inner wall.

24. As an article of manufacture, a sole for incorporation in a turn shoe, said sole being provided with a stitch receiving portion in its forepart and shank and with a shortened and narrowed heel portion so shaped as to terminate short of the heel end of the heel seat of a lasted shoe to which it is to be attached and to engage the greater part of the generally concave heel seat surface of a previously completed heel when attached to the shoe.

25. As an article of manufacture, a sole for incorporation in a shoe, said sole having a heel portion which is narrower than the adjoining shank portion and offset inwardly therefrom by two shoulders, is shorter than the heel portion of the lasted shoe to which it is to be attached and has a convex under side to fit the cavity in the top of a wood heel.

In testimony whereof I have signed my name to this specification.

GEORGE FERGUSON.
